UNITED STATES PATENT OFFICE.

WILLIAM PHIPPS, OF MILWAUKEE, WISCONSIN.

IMPROVEMENT IN STOVE-GRATES.

Specification forming part of Letters Patent No. 222,365, dated December 9, 1879; application filed April 16, 1879.

To all whom it may concern:

Be it known that I, WILLIAM PHIPPS, of the city of Milwaukee, in the county of Milwaukee and State of Wisconsin, have invented certain new and useful Improvements in Stove-Grates; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to improvements in grates for fire-boxes of stoves, furnaces, &c.

The object of my invention is to provide a grate for sifting the ashes from coal within the fire-box, and also for dumping the coal or clinkers from the stove after having first separated the ashes therefrom, the construction of which is such that it is not liable to become choked up or locked in a rigid position by coal or clinkers, and which is more easily operated and more effectual in accomplishing the end desired than the ordinary grates now in use.

Heretofore it has been customary to construct grates with their bars nearly or quite straight, and to arrange them in a horizontal position within the fire-box, and to provide the same with a central shaft or trunion, by means of which the grate could be turned edgewise when it is desired to dump the coal, or partially so when it is desired to shake the ashes therefrom.

It is obvious that the edges of the horizontal or flat grate are liable to become frequently clogged with coal and clinkers when being shaken, and the coal is also liable to escape from the fire-box with the ashes.

By my device the bars of the grate move alike bodily across from one side of the fire-box to the other beneath the coal, thus thoroughly sifting the ashes from all parts of the fire-box alike, while there is no opportunity for the coal to escape when shaking, or for the grate to become clogged with coal or clinkers,

all of which is further explained by reference to the accompanying drawings, in which—

Figure 1 represents a top-plan view of my invention. Fig. 2 represents a vertical transverse section of the same. Fig. 3 represents a perspective view of the same, having a part of the fire-box removed.

In the accompanying drawings, like parts are indicated by the same reference-letters.

A is the fire-box, which is provided with a cylindrical grate consisting of a series of circular bars or rings, C, connecting-bars D, heads E, trunnions F, and longitudinal section G, all of which constituent parts of the cylinder may be cast in one piece, with the exception of the longitudinal section G, which is made detachable.

The object of providing the grate with the detachable section is to facilitate the removal of coal or clinkers from the fire-box, which is accomplished by removing the detachable section and half revolving the grate, so that the contents of the fire-box will drop into the ash-pit through the space from which section G has been removed.

When the section G is attached the cylinder may be revolved either continuously forward or backward, or alternately forward or backward, until the ashes are separated from the coal.

H is a metallic rod or roller, which lies loosely in the cylinder, and is caused, by its own gravity, to roll upon the ashes as the cylinder is revolved, and thus prevents it from being choked up thereby.

I is an opening through the head of the cylinder for inserting a poker when it is required.

J is the end of the fire-box, provided with lugs K, against which the handle L may be caused to strike, if desired, to jar the grate.

When it is desired to turn the grate entirely over, or to revolve it, the handle is drawn slightly forward, so as to escape contact with the lugs.

The ends of the fire-box are each provided with circular flanges M, which slightly overlap the end of the grate. The sides of the fire-

box are also provided with flanges N, which project slightly between the bars C, to prevent coal from escaping from the box.

Having thus described my invention, what I claim as new, and desire to secure by Letters Patent, is—

In combination with a fire-box, A, provided with flanges M and flanges N and lugs K, of the revolving cylindrical grate, consisting of rings C, bars D, provided with heads E, and

trunnions F, all substantially as and for the purpose specified.

In testimony that I claim the foregoing as my own I affix my signature in presence of two witnesses.

WILLIAM PHIPPS.
